The ornamental design for a charge card with a display and a fingerprint reader, as shown and described.

DESCRIPTION

FIG. 1 is a perspective view of a charge card with a display and a fingerprint reader, showing a first embodiment of my new design;

FIG. 2 is a front elevational view of FIG. 1;

FIG. 3 is a rear elevational view of each embodiment;

FIG. 4 is a left-side elevational of each embodiment, the right-side elevational view being a mirror image thereof; FIG. 5 is a top plan view of each embodiment, the bottom plan view being a mirror image thereof;

FIG. 6 is a cross-sectional view thereof, taken along line 6-6 of FIG. 2;

FIG. 7 is a perspective view of a second embodiment thereof;

FIG. 8 is a front elevational view of FIG. 7;

FIG. 9 is a perspective view of a third embodiment thereof;

FIG. 10 is a front elevational view of FIG. 9;

FIG. 11 is a perspective view of a fourth embodiment thereof;

FIG. 12 is a front elevational view of FIG. 11;

FIG. 13 is a perspective view of a fifth embodiment thereof;

FIG. 14 is a front elevational view of FIG. 13;

FIG. 15 is a perspective view of a sixth embodiment thereof; and,

FIG. 16 is a front elevational view of FIG. 15.

The broken lines in the figures depict portions of the charge card with a display and a fingerprint reader that form no part of the claimed design. FIGS. 3-5 represent a common rear elevational view, left side elevational view, right side elevational view, top plan view, and bottom plan view of all embodiments.
